UNITED STATES PATENT OFFICE

147,218

DESIGN FOR A BELT BUCKLE

John R. Hampel, Pewaukee, Wis., assignor to
Milwaukee Saddlery Company, Milwaukee,
Wis., a corporation of Wisconsin

Application May 24, 1946, Serial No. 130,058

Term of patent 14 years

(Cl. D17—1)

To all whom it may concern:

Be it known that I, John R. Hampel, a citizen of the United States of America and residing at Pewaukee, in the county of Waukesha and State of Wisconsin, have invented a new, original, and ornamental Design for a Belt Buckle, of which the following is a specification, reference being had to the accompanying drawings, forming a part thereof.

In the drawings:

Fig. 1 is a front elevational view of a belt buckle showing my new design;

Fig. 2 is a side elevational view of the belt buckle;

Fig. 3 is a rear elevational view of the belt buckle.

I claim:

The ornamental design for a belt buckle, as shown.

JOHN R. HAMPEL.
